UNITED STATES PATENT OFFICE

ALBERT J. GIFFORD AND BENJAMIN S. T. BISHOP, OF SHREWSBURY, MASSACHUSETTS,
ASSIGNORS TO LELAND-GIFFORD COMPANY, OF WORCESTER, MASSACHUSETTS, A
CORPORATION OF MASSACHUSETTS

OIL PUMP

Application filed February 3, 1926, Serial No. 85,695. Renewed May 10, 1930.

This invention relates to a pump for circulating lubricating oil and feeding it to a machine in which it is to be used on the work or tool.

The principal objects of the invention are to provide a simple form of gear pump for this purpose having means whereby the lubricant will be introduced into the pump and discharged therefrom on the same side of the pump for saving piping and space; to provide a by-pass whereby, when it is desired to feed no more oil to the machine, although the machine may be running, the oil will continue to be circulated within the pump without being discharged; to provide simple means for mounting the pump and connecting it with the power, and to provide all these features in a compact form.

Reference is to be had to the accompanying drawings in which—

Fig. 1 is a side view of a drill showing a lubricating pump and connections thereon arranged in accordance with this invention;

Fig. 2 is a front view of the pump and means for operating it, showing the connections between them in central section;

Fig. 3 is a similar view of the pump by itself;

Fig. 4 is an end view of the pump;

Fig. 5 is a central sectional view on the line 5—5 of Fig. 4;

Fig. 6 is a sectional view on the line 6—6 of Fig. 5;

Fig. 7 is a sectional view along the line 7—7 of Fig. 3 through the oil outlet;

Fig. 8 is a sectional view along the line 8—8 of Fig. 5 showing the valve for controlling the by-pass;

Fig. 9 is a view similar to Fig. 2 showing a way of mounting the pump to be driven by a pulley on the shaft thereof;

Fig. 10 is a side view of a machine like that shown in Fig. 1 showing the pump mounted to be driven directly by a motor; and

Fig. 11 is a horizontal sectional view on the line 11—11 of Fig. 10 showing the connection with the motor.

This invention is designed for circulating lubricating oil in a metal working machine

and we have shown it as applied to one type of drill 10. In Fig. 1 the oil is drawn up from a reservoir 9 through a pipe 11 through the pump 21 and discharged through a pipe 14 on the work or drill. In this case the 55 drill is driven through a power shaft 15 having cone pulleys 16 for driving the drill spindle. This power shaft is supported by ball bearings 17 on the frame 10 of the machine and has a diametrical tongue 18 at 60 its end.

The cap which is usually provided over the end of this shaft is removed and in its place is fixed a casing 20 which has secured to it the pump casing 21. We will not describe the pump fully here except to say that it has a shaft 22 on which is slidingly keyed a clutch 23 operated by a handle 24 and eccentric 25 working on a groove on the clutch. This clutch 22 engages the projection 18 on 70 a shaft 15 to drive the pump positively from that shaft.

Before describing the pump, we will also call attention to Fig. 9 in which the same pump casing 21 and shaft 22 are used. In 75 this case the shaft 22 extends through the support 26 on which the casing 21 is fixed and is provided with a pulley 27 or other means for rotating it. The frame 26 can be located on the floor or base of the machine 80 for the same purposes as in the other figures. Also in Figs. 10 and 11 we have shown the pump 21 mounted at the base of the column 10 of the machine and operated by a motor 28 driving it directly by a gear 29 to the 85 shaft 22.

No matter how mounted, the pump is constructed in the same way in all cases. It might be stated that in the form shown on the second sheet of drawings the pump shaft 22 is provided with a clutch 23 for receiving the projection 18 which has been described for securing the direct connection here. The shaft 22 is provided with a gear 32 meshing with a gear 33 on an idle shaft 34, these gears constituting the pump proper and operating to drive the oil through the course which it is designed for it to take. The shafts of the two gears are mounted in the frame in a well known way, a stuffing 100

box 35 being provided to protect one of them from the escape of oil from the pressure side.

The course of the oil is from the inlet pipe 11 through an inlet passage 36 at one side of the gears and over and around them to bring the oil clear from one side of the case around the gears to the other side where it enters between them, as shown in Fig. 6. From the gears the oil passes through an outlet passage 37 to the discharge pipe 14 and is driven out of the pump there. It will be noted that the passage 37 is on the same side of the gears as the intake end of the passage 36 but they are separated from each other lengthwise by an internal wall of the casing. The passage 36 through the casing is also offset from the entrance end and it is provided with a screw plug 38 for use in filling.

Through an internal separating wall of the casing there is an L-shaped by-pass 40 extending from the outlet passage 37 into the passage 36. Where it enters the latter it is provided with a valve seat 41 closed by a valve 42 pressed to its seat by a spring 43 and capable of adjustment by a screw plug 44. When it is desired to shut off the oil from the work, as is often necessary or at least important from the standpoint of economy, this screw plug 44 is turned outwardly to relieve the tension on the spring 43 so that the ordinary pressure of the oil in the by-pass 40 will open the valve 41. Now the oil flows from the gears through the by-pass 40 past the valve 41 and back into the passage 36. In this way the oil will circulate continuously in the pump until the screw plug is again adjusted to cause it to be delivered through the outlet pipe 14.

This constitutes a very compact and light pump for the purpose described which can be filled through the screw plug 38 to the oil level indicated in Fig. 6 and will then continue to operate at substantially that level and which will circulate the oil in it with the machinery running when it is desired to change a tool or to replace the work. The oil is introduced and discharged at the same side of the pump, thus saving piping and space. It is capable of being applied to a tool similar to a high speed drill or to tools of other characters in many ways as have been shown.

Although we have illustrated and described only a single form of the invention and shown only three ways of applying it, we are aware of the fact that other changes can be made therein by any person skilled in the art without departing from the scope of the invention as set forth in the claim.

Therefore, we do not wish to be limited in these respects, but what we do claim is:

In a gear pump for a lubricating system, the combination with a pair of gears mesh-

ing with each other for pumping a liquid and means for driving one of the gears, of a casing surrounding the gears, said casing having an inlet passage extending from one side thereof around one of said gears and into a position to deliver all of the liquid to the inlet side of the gears on the opposite side of said casing, and an outlet passage from the gears direct and on the same side of the casing as the inlet passage and adjacent thereto.

In testimony whereof we have hereunto affixed our signatures.

ALBERT J. GIFFORD.
BENJAMIN S. T. BISHOP.
